(57) **CLAIM**

The ornamental design for a vibratory massager, as shown and described.

DESCRIPTION

FIG. 1 is a top perspective view of a vibratory massager, including features shown in broken lines that are not part of the claimed design.

FIG. 2 is a top plan view thereof.

FIG. 3 is a bottom plan view thereof.

FIG. 4 is a left side elevation view thereof.

FIG. 5 is a right side elevation view thereof.

FIG. 6 is a rear end view thereof; and,

FIG. 7 is a front end view thereof.

The broken lines shown on the drawings are for illustrative purposes only and form no part of the claimed design.
